US00D589028S

(12) **United States Design Patent**
Haapapuro et al.

(10) **Patent No.:** **US D589,028 S**
(45) **Date of Patent:** **** Mar. 24, 2009**

(54) **LOW PROFILE MICROPHONE TIP ASSEMBLY**

(75) Inventors: **Andrew Haapapuro**, Arlington Heights, IL (US); **Viorel Drambarean**, Skokie, IL (US)

(73) Assignee: **Etymotic Research, Inc.**, Elk Grove Village, IL (US)

(**) Term: **14 Years**

(21) Appl. No.: **29/299,751**

(22) Filed: **Jan. 3, 2008**

(51) LOC (9) Cl. **14-01**

(52) U.S. Cl. **D14/206**; D14/225

(58) **Field of Classification Search** D14/188, D14/192, 218, 226, 227, 228, 229, 299, 205, D14/206, 223; D13/168; 181/158, 242; 379/430, 431; D10/106; 381/91, 168, 169, 381/170, 357, 361, 362, 353, 369

See application file for complete search history.

(57) **CLAIM**

The ornamental design for a low profile microphone tip assembly, as shown and described.

DESCRIPTION

FIG. 1 is a perspective view of a low profile microphone tip assembly showing my new design, the broken line showing of the human form is for illustrative purposes only and forms no part of the claimed design;

FIG. 2 is a perspective view of the microphone tip assembly thereof;

FIG. 3 is a perspective view of the microphone tip assembly thereof;

FIG. 4 is a rear elevation view thereof;

FIG. 5 is a top plan view thereof;

FIG. 6 is a front elevation view thereof;

FIG. 7 is a left side elevation view thereof; and,

FIG. 8 is a right side elevation view thereof.

The even broken lines in the drawings are for illustrative purposes only and form no part of the claimed design.
